PUSH BUTTON SLIDE ASSEMBLY FOR TUNERS
John H. Teaf, Merchantville, N.J., assignor, by mesne assignments, to Thompson Ramo Wooldridge Inc., Euclid, Ohio, a corporation of Ohio
Filed May 26, 1961, Ser. No. 112,962
9 Claims. (Cl. 74—10.33)

The invention relates to improved push button slide assemblies for ratio tuners, particularly those of the type used in automobiles.

In automobile type radios tuning may be effected by the manual depression of push buttons preset to different broadcasting stations. For a background description of the overall tuner structure reference may be made to my prior Patents No. 2,848,900 and No. 2,898,767, dated August 26, 1958, and August 11, 1959, respectively. The actual tuning, of course, is effected by the positioning of magnetic cores in coils, forming variable inductances in the tuning circuits, through means including slide assemblies operable by such push buttons. Each slide assembly comprises, in brief, a pair of slide members, a cam element for adjustment of magnetic core positioning treads, bars, and a locking lever for the cam element. Inward relative sliding movement of these members effects locking of the cam element by the lever at a predetermined setting and outward relative sliding movement effects release of the cam element to permit a change in such setting.

It will be understood that a push button is secured to the shank of one of the slide members of each slide assembly, and this push button projects through a front panel of the tuner which is integrated with the instrument panel or otherwise mounted inside the vehicle. Typically, a plurality of push buttons, say five, are closely arranged in the front tuner panel in a vertical or horizontal row. The general appearance of the visible front tuner panel and other portions of the radio and its keeping with the interior decorative scheme of the vehicle are, of course, matters of concern.

The invention concerns particularly the problem of maintaining neat and proper alignment of the row of these push buttons. For various reasons appearing presently, the push buttons may tend to present an unpleasant appearance of misalignment. As mentioned, a push button slide assembly of the type under consideration is comprised of slide members that are relatively movable to lock and unlock the cam element. These members may become loose, and even though the slide members are in locked position, the slide member bearing the push button may be movable transversely to the other slide member and to the row of push buttons to a limited extent. Looseness of the members may be caused by a number of factors, though probably the most common is that of progressive wear. Also, a push button may be accidentally bumped, or may be roughly mistreated, thereby damaging slightly the slide assembly and enlarging the original clearances between the slide members. A further cause of looseness may be that the push button and its associated slide member may be purposely or inadvertently stressed transversely of the other slide member, though the tuner was not designed or intended for such handling. To the end that play of parts might be minimized, in order thereby to discourage undesired misalignment of push buttons, it has been thought necessary to maintain close manufacturing tolerances in manufacture of the slide assembly. Obviously, therefore, liberalizing of manufacturing tolerances, while nevertheless attaining the desired result, would represent a definite advantage.

Accordingly, it is an object of the invention to provide a push button slide assembly whereby a row of push but-

tons in a tuner will maintain proper alignment despite looseness of the parts thereof due to various causes.

Further objects and advantages will become apparent from the following description, read in conjunction with the following drawings in which:

FIGURE 1 is an illustration of the front panel of a tuner;

FIGURE 2 is a side view of a push button slide assembly according to the invention, the assembly being shown in its locked position;

FIGURE 3 is a bottom view of the slide assembly shown in FIGURE 2;

FIGURE 4 is a bottom view of the slide assembly, the assembly here being in the unlocked position; and

FIGURE 5 is a view from the left end of the slide assembly as shown in FIGURE 4.

Referring to FIGURE 1, there is illustrated that portion of a radio which normally is visible when it has been installed in a vehicle, namely, the front panel 2 having the usual dial 4, on-off and volume knob 6, manual tuning knob 8 and tuning push buttons 10. Referring next to FIGURES 2 and 3, there is shown an individual slide assembly 12, each push button having one of these assemblies associated therewith and operated thereby to effect tuning to a preset broadcasting station. Assembly 12 comprises generally a pair of slide members 14 and 16, previously mentioned, the member 16 having a tang or shank 18 adapted to receive one of the push buttons 10. Though the basic structure of assembly 12 is the same as that disclosed in said Patent 2,848,900, and similar in principle to said Patent 2,898,767, it will briefly be described herein. First, it may be noted that member 14 has edges 15 and 17 which cooperate with slots in the tuner frame (not shown), whereby transverse motion of the slide members is restricted and they are guided for longitudinal motion. A bracket 20 riveted to member 14 has an upstanding portion 22 which provides a fulcrum for a lever 24. The left end of lever 24 is adapted to be forced upwardly, against the action of a spring 26 which also is riveted with bracket 20 to member 14, by means of a cam 28 projecting from slide member 16. It may be noted that, as viewed in FIGURE 2, cam 28 has a downwardly turned portion 30 which projects through a slot 32 in member 14 and engages the bottom of the member adjacent the slot so as to hold members 14 and 16 in sliding relationship. At its right end lever 24 is provided with bosses 34 adapted to engage and tightly grip the cam element 36 previously mentioned. Thus the camming upwardly of the left end of lever 24, upon inward movement of member 16 relative to member 14, results in the movement downward of bosses 34 to lock cam 36 in position. It may be noted further that the right end 38 of spring 26 acts upwardly against the right end of lever 24, tending to disengage the same from the cam 36 upon sliding movement of member 16 to the left as viewed in FIGURE 2. The spring 26 is provided merely as an anti-rattling device.

Passing to matters of greater interest, the member 16 is guided for sliding movement relative to member 14 by means of the legs 42 and 43 which are formed by turning downwardly the sides of slide member 16. Guidance is also provided to some extent by the cooperation of extension 30 and slot 32. There has been mentioned previously the fact that a loose sliding fit between the slide members will give rise to misalignment of the push buttons, which is unsatisfactory from the standpoint of appearance. There is indicated in the drawings an overall clearance *c* between the left end of member 14 and the legs 42 and 43, and it will be evident that this clearance will determine the amount by which the tang or shank end (18) of member 16 may be moved up or down (in the plane of FIGURE 3 or 4) with respect to the

member 14. As previously explained, for purposes of economical manufacture it is desirable to avoid the necessity of small manufacturing tolerances in respect of the clearance c in particular. Furthermore, absent the details described hereafter, the clearance c may be enlarged either through wear or by mistreatment. Thus, if in FIGURE 3 or 4 the left end of member 16 is forcibly moved up or down (in the plane of the drawings) with respect to the member 14 the legs 42 and 43 naturally will tend to bend outwardly, thereby increasing the clearance c and the play between members 14 and 16.

According to the invention the above problems are avoided by provision of a slot 44 in the member 14 and a boss or projection 47 on member 16. The width of slot 44 is only very slightly greater than the diameter of the round boss 47, and when the slides are in their relatively inward locked position as shown in FIGURE 3 the boss 47 projects into and is closely held against lateral movement by the slot 44. It will be noted that the mouth of the slot 44 is bevelled as indicated at 46 to guide boss 47 into slot 44 in its movement from the FIGURE 4 to the FIGURE 3 condition. Thus, according to the invention, means (44, 47) are provided to restrict lateral play between the slide members despite ineffectiveness of the means (42 and 43) provided primarily for guiding the slide members.

In an ordinary slide assembly, i.e. one in which slot 44 and boss 47 are not provided, the slide members may be angularly shifted back and forth within limits and to the extent of the clearances existing therebetween. For example, assuming the case of such an "ordinary" assembly, if the shank end 18 of member 16 is urged downwardly as viewed in FIGURE 3, the members 14 and 16 will assume a relative position which deviates from axial alignment by an angle determined by the clearance between member 14 and respectively the left end of leg 42 and the right end of leg 43. Also, if the shank end is urged upwardly, relative shifting between the members will occur to the extent of an angle determined by the clearance between member 14 and respectively the right end of leg 42 and the left end of leg 43. The overall possible misalignment of the members is represented by an angle equalling the sum of the angles in the above assumed case, and such overall misalignment therefore will be undesirably large. According to the invention, however, the possible angle of misalignment will be comparatively slight. It will be seen that at the location of the left end of member 14, by virtue of slot 44 and boss 47, the members 14 and 16 are restrained against any lateral shifting due to clearances between member 14 and the respective legs 43 and 42 at such location. Thus any angular misalignment will be limited to the extent of a very small angle determined only by clearances, if any, at the right ends (FIGURES 2-4) of legs 43 and 42. The last-mentioned angle thus will represent a small fraction of the previously explained overall possible angle of misalignment in an ordinary slide assembly.

It will be understood that various departures from the specifically disclosed embodiment of the invention may be made without departing from the scope thereof as defined by the following claims.

What is claimed is:

1. A tuner slide assembly comprising first and second elongate slide members overlapping each other for a portion of their respective lengths, means holding said members in sliding relationship to each other, means guiding said members for relative sliding movements between outer and inner first and second positions respectively, a cam element pivotally mounted on one of said members, means operable by inward relative sliding movement of said members to lock said cam element against rotation, and separate, additional means restricting lateral play between said members, in a direction transverse to the length thereof, due to incomplete effectiveness of said guiding means.

2. An assembly according to claim 1, wherein the last-mentioned means comprises a projection on one of said members, and an elongate slot formed in the other of said members and aligned with the length thereof, said projection extending into said slot and being slidable therein with small clearance during relative sliding movements of said members.

3. An assembly according to claim 2, wherein said slot extends inwardly from one end of said one member on which the cam element is mounted, said end being overlapped by the other said member carrying said projection.

4. A tuner slide assembly comprising first and second elongate slide members overlapping each other for a portion of their respective lengths, means holding said members in sliding relationship to each other, one of said members having at least one of its side edges turned against a side edge of the other of said members for guiding of the members in relative sliding movements between inner and outer positions respectively, a cam element pivotally mounted on one of said members, means operable by inward relative sliding movement of said members to lock said cam element against rotation, and separate, additional means restricting lateral play between said members, in a direction transverse to the length thereof, due to excessive clearance between said side edges.

5. An assembly according to claim 4 wherein the last-mentioned means comprises a projection on one of said members and an elongate slot formed in the other of said members and aligned with the length thereof, said projection extending into said slot and being slidable therein with small clearance during relative sliding movements of said members.

6. An assembly according to claim 5, wherein said slot extends inwardly from one end of said one member on which the cam element is mounted, said end being overlapped by the other said member carrying said projection.

7. A tuner slide assembly comprising first and second elongate slide members overlapping each other for a portion of their respective lengths, means holding said members in sliding relationship to each other, one of said members having opposite side edges turned against opposite side edges of the other of said members for guiding of the members in relative sliding movements between inner and outer positions respectively, a cam element pivotally mounted on one of said members, means operable by inward relative sliding movement of said members to lock said cam element against rotation, and separate, additional means restricting lateral play between said members, in a direction transverse to the length thereof, due to excessive clearance between said side edges.

8. An assembly according to claim 7, wherein the last-mentioned means comprises a projection on one of said members, and an elongate slot formed in the other of said members and aligned with the length thereof, said projection extending into said slot and being slidable therein with small clearance during relative sliding movements of said members.

9. An assembly according to claim 8, wherein said slot extends inwardly from one end of said one member on which the cam element is mounted, said end being overlapped by the other said member carrying said projection.
